Mahlon R. Marjerum

United States Patent Office.

MAHLON R. MARGERUM, OF TRENTON, NEW JERSEY.

Letters Patent No. 82,333, dated September 22, 1868; antedated September 9, 1868.

IMPROVEMENT IN COFFINS.

The Schedule referred to in these Letters Patent and making part of the same.

TO ALL WHOM IT MAY CONCERN:

Be it known that I, MAHLON R. MARGERUM, of the city of Trenton, county of Mercer, and State of New Jersey, have invented a new and improved Mode of Constructing Wooden Coffins; and I do hereby declare that the following is a full and exact description thereof, reference being had to the accompanying drawings, and to the letters of reference marked thereon.

The nature of my invention consists in constructing a round-headed coffin with two boards properly shaped and bent, and joined together at the head, so as to form the two sides and rounded head of the coffin; the top, bottom, and foot-board of the said coffin to be made and joined thereto in the common and usual way.

In Figure 1, A B C D represents one of the boards, shaped and bent to form one of the sides and half of the rounded head of the coffin. The other side or counterpart, (not shown in the drawing,) is made similar, but bent in an opposite direction; that is, one board is bent turning to the right hand, and the other, or counterpart, to the left. The edges A B of the two boards may butt together, or, the mode which I prefer, and consider as part of my improvement, is to join them together with a tongue and groove, cut on the edges of the boards, and to fasten them together with a dove-tailed clasp.

In Figure 2, A B E F G H represent the bent portions of the two boards, enclosing the rounded head of the coffin. A B shows the tongued and grooved joint, and K M K the dove-tailed clasp.

I do not claim broadly the making of round-head coffins; neither do I claim any particular process for bending the boards, as that can readily be done by the common method of steaming, or the like; but

What I do claim as my invention, as a new article of manufacture, and desire to secure by Letters Patent, is—

The forming and constructing the side and rounded head of wooden coffins with two entire pieces of wood, and bending the same so as to form the coffin, substantially as above described and herein set forth.

MAHLON R. MARGERUM.
